US0D1015668S

(12) **United States Design Patent** (10) Patent No.: **US D1,015,668 S**
 Harrington et al. (45) Date of Patent: ** Feb. 20, 2024

(54) **FLOOR CLEANING SYSTEM**(71) Applicant: **Unger Marketing International, LLC**,
Bridgeport, CT (US)(72) Inventors: **William Harrington**, Newtown, CT
(US); **Robert F. Smith**, Waterbury, CT
(US)(73) Assignee: **Unger Marketing International, LLC**,
Bridgeport, CT (US)(**) Term: **15 Years**(21) Appl. No.: **29/802,872**(22) Filed: **Aug. 9, 2021**
